UNITED STATES PATENT OFFICE.

WILLIAM C. PFEIFFER, OF CHICAGO, ILLINOIS.

STEAM-BOILER.

No. 878,892.

Specification of Letters Patent.

Patented Feb. 11, 1908.

Application filed June 4, 1906. Serial No. 319,981.

To all whom it may concern:

Be it known that I, WILLIAM C. PFEIFFER, a citizen of the United States, residing at Chicago, in the county of Cook and State of Illinois, have invented certain new and useful Improvements in Steam-Boilers, of which the following is a specification.

One of the objects of this invention is the production of an improved steam boiler adapted for high-pressure service.

Another object of the invention is the production of an externally-fired, return-tubular boiler requiring no inclosing brickwork.

A further object is the production of an improved means for staying or bracing steam boilers.

The invention further refers to the various other features of improvement hereinafter shown and described.

In the accompanying drawings, Figure 1 is a vertical central longitudinal section through a steam boiler embodying the features of my invention. Fig. 2 is a rear end elevation of said boiler, a portion of the boiler being shown in section on the plane of dotted line 2—2 of Fig. 1. Fig. 3 is a transverse sectional view through the boiler on dotted line 3—3 of Fig. 1.

In the embodiment herein shown of this invention the boiler shell comprises two cylindrical sections 1 and 2 secured end to end, the rear section 2 being of greater diameter than the forward section 1. Within the forward end of the forward shell-section 1 is secured the tube sheet 3, and closing the forward end of said section is the wall 4. The tube sheet 3 and the wall 4 provide between them a smoke box 5 communicating with the smoke stack through the flue 6. The rear end of the rear shell-section 2 is closed by the tube sheet 7, and the forward end of said section is provided with a tube sheet 8 having therein a circular opening 9 adapted to receive the rear end of the forward shell-section 1. Said forward section 1 is secured to the sheet 8 by means of rivets 10 extending through the shell 1 and through an annular flange 11 formed integral with said sheet. As shown in Fig. 1, the rear end of the section 1 beyond the point of union with the tube sheet 8 is notched or cut away to provide a plurality of tongues 12 (in this instance, six in number), which tongues project into the rear section 2 and furnish a means of attachment for stays 13 connecting the rear tube sheet 7 with

the rear end of the section 1. Said stays have split forward ends to receive the tongues 12, to which tongues they are attached by means of the rivets 14. The rear ends of the stays 13 are of crow-foot form and are secured to the head 7 by rivets 15. Tubes or flues 16 extend through the sections 1 and 2, said tubes being expanded into the tube sheets 3 and 7. Tubes 17, somewhat larger in diameter than the tubes 16, extend through the rear section 2 between the heads 7 and 8. Communication between the rear ends of the flues 16 and 17 is established through a chamber 18. Said chamber comprises an extension 19 of the rear section 2 supporting a rear wall 20 of tile or brickwork, and a top wall 21. Access to the flues 16 and 17 for cleaning and repair is had through suitable doors (not shown) in the walls 4 and 20. A man-hole 22 is formed in the rear tube sheet 7 above the flues 16, and handholes 23 and 24 in the lower portions of the tube sheets 3 and 7, respectively. Diagonal stays 25 are secured to the tube sheets 3 and 7 above the flues 16, and to the upper part of the shell-sections 1 and 2. In the lower side of the rear section 2 is provided a clean-out opening 26.

The furnace with which this boiler is herein represented as provided comprises the front wall 27, the rear wall 28 and the side walls 29. The forward end of the boiler is supported by means of lugs 30 resting upon the side walls 29, and the rear end of the boiler rests upon a pillar or standard 31 of any suitable form. The grate 32 extends between the front wall 27 and the bridge wall 33. As shown in Fig. 1, the bridge wall 33 is located a slight distance forwardly of the tube sheet 8, providing a space 34 between the rear end of the grate 32 and said tube sheet. Access to the space 34 for cleaning purposes is had through an opening 35 in one of the side walls 29, said opening being closed by a door 36. If desirable, a slide or shutter (not shown) may be provided in the door 36 for admitting air to the combustion chamber 37. One or more openings 38 are formed in the front wall 27 to give access to the combustion chamber 37, said openings being closed by suitable furnace doors 39. An opening 40 in the front wall 27 affords access to the ash-pit 41, said opening being closed by the door 42. The rear shell-section 2 and the upper part of the section 1

may be provided with a non-conducting covering (not shown) of asbestos or other suitable material.

In operation, the products of combustion 5 pass from the combustion chamber 37 through the flues 17, the chamber 18, the flues 16 and the smoke box 5 to the smoke flue 6. The arrangement of boiler and furnace herein shown obviates the necessity for 10 bricking in the boiler, the path of the products of combustion in passing from the furnace to the smoke outlet being entirely within the boiler and the connecting chamber 18. It will be noted that the relative 15 lengths of the shell-sections 1 and 2 are such as to provide space for the use of a large grate surface, thus giving the boiler large steam - raising capacity. To enable it to carry comparatively high steam pressures, 20 the boiler shell is made cylindrical throughout its length, and the heads or tube sheets are thoroughly stayed by means of the stays 13 and 25. The stays 13 being connected to the shell-section 1 at a point within the shell 25 2 are not exposed to the intense heat of the fire. In cleaning the boiler a hose may be introduced into the handhole 23 and the in-

terior of the boiler flushed, the mud and loose scale being discharged through the clean-out opening 26.

35

I claim as my invention:

1. In a steam boiler, in combination, a shell comprising two aligned cylindrical sections, the forward section being of smaller diameter than the rear section and projecting into said rear section, said rear section being provided with a rear tube sheet; and stays engaging said rear tube sheet and the inwardly-projecting rear end of said forward section.

40

2. In a steam boiler, in combination, a shell comprising two aligned cylindrical sections, the forward section being of smaller diameter than the rear section and projecting into said rear section, said inwardly-projecting rear end being notched to provide tongues; a tube sheet for the rear end of said rear shell-section; and stays secured to said tube sheet and said tongues.
